CONVEYER

Richard S. Jacobsen, Los Angeles, Calif.

Application March 5, 1945, Serial No. 580,972

8 Claims. (Cl. 198—220)

1

This invention relates to power driven conveyers and more particularly to conveyers of the type that move material therealong by an oscillatory movement of the conveyer which is of such a nature that it imparts a tossing action to material carried by the conveyer, whereby that material is advanced along the conveyer in a succession of regularly repeated step-by-step actions without requiring any downward slope of the conveyer in the direction of advance.

The nature, extent, and frequency of the oscillatory movement of the conveyer necessary to result in movement of material therealong are explained with adequate particularity in Patent No. 2,123,189 issued to me on July 12, 1938; and it is an object of my present invention to provide improvements in the construction of the conveyer structure and in the actuating mechanism therefor whereby their durability, dependability and efficiency of operation are materially improved as compared with those of the corresponding structures disclosed in my said issued patent.

A further object in this connection is to improve the construction of the conveyer trough in such a manner as to enlarge its range of adaptability both with respect to the limitations of space available for the conveyer's installation and with respect to the character of material to be carried by the conveyer.

A more detailed object in this connection is to provide in conveyer apparatus of the character indicated, a trough structure which, instead of being in the form of a continuous run rigid throughout its entire length, is made up of a plurality of separate sections so loosely joined that expansion and contraction of one or more of the sections can occur without interference with the conveyer's efficiency, thus adapting the conveyer for carrying materials at any of a wide range of temperatures, as well as at widely varying temperatures.

A further object is to modify the supporting and actuating mechanism for the conveyer in such a manner that it serves to support and operate two separate and independent conveyers carrying material in opposite directions.

A still further object is to provide an actuating mechanism for a conveyor of the general character described which is adapted to operate two conveyors extending angularly with respect to each other, or a single conveyer, separate portions of which extend angularly with respect to each other, thus avoiding the necessity of providing a separate source of power for each conveyer, or for each conveyer section, as the case might be.

10

The invention possesses other objects and valuable features, some of which, with those enumerated, will be set forth in the following description of the preferred embodiments of my invention illustrated in the drawing accompanying and forming a part of the specification. It is to be understood that I do not limit myself to the showing made by said drawing and description but that I may adopt variations of the preferred forms within the scope of my invention as defined by the claims.

Referring to the drawings:

Figure 1 is a longitudinal, medial, vertical sectional view of a portion of a conveyer incorporating the principles of the present invention and showing the manner of its connection to its source of actuating power.

Figure 2 is a view in side elevation showing another portion of the conveyer of Figure 1 to illustrate the manner in which trough sections are associated with each other to form a continuous trough.

Figure 3 is a transverse, vertical sectional view taken upon the line 3—3 of Figure 2 with the direction of view as indicated.

Figure 4 is a top plan view of the actuating mechanism and power source of Figure 1. This figure may be considered a compound, horizontal sectional view taken upon the lines 4—4 of Figure 1 with the direction of view as indicated.

Figure 5 is an enlarged, detail view of the trough sections and actuating mechanism of Figure 2, portions of the figure being broken away to reduce its size.

Figure 6 is a view similar to Figure 2, but illustrating a modified form of construction whereby two oppositely flowing conveyers are operated by a single actuating mechanism.

Figure 7 is a transverse vertical sectional view taken upon the line 7—7 of Figure 6 with the direction of view as indicated.

Figure 8 is a top plan view showing portions of two angularly extending conveyers, one of which receives its load from the other, both conveyers being operated by a single power source.

Figure 9 is a vertical sectional view taken upon the line 9—9 of Figure 8 with the direction of view as indicated.

Referring first to that modification of my present invention which is illustrated in Figures 1 to 5 inclusive, it will be seen that, as in the case of the conveyer forming the subject matter of my said issued patent, the trough 11 advantageously can be constructed of any suitable material, sheet metal being preferable, however,

30

40

35

45

55

inasmuch as one of the details of the present invention particularly adapts my conveyer for use in carrying materials at high temperatures.

With this object in view, the trough 11, instead of being constructed of one long continuous run of trough, supported at a plurality of points by several supporting and actuating mechanisms 12, consists of a plurality of relatively short trough sections 13, 14, etc. Each trough section is supported at only one point, that point being adjacent its inlet end 16, whereas the outlet end 17 of each section, instead of being connected directly to any supporting and actuating mechanism, merely rests upon the inlet end 16 of the next successive section in the direction in which material carried by the conveyer is moved. That is to say, if the section 13 is the first or beginning trough section in a run of conveyer trough 11, it is directly connected to its supporting and actuating mechanism 12 only adjacent its inlet end 16, (see Figure 1) whereas its outlet end 17 (see Figure 2) is supported merely by resting upon the inlet end 16 of the next successive trough section 14, i. e., the second trough section of that same run of conveyer trough 11. Preferably the trough sections 13, 14, etc., are so dimensioned that the outlet ends 17 are slightly smaller than their inlet ends 16 so that the former can nest nicely within the inlet end 16 of the next successive trough section.

The several trough sections 13, 14, etc., are not positively locked together. Instead, they are held in contact with each other only by gravity. As the result of this arrangement, relative sliding movement of the interengaging portions of adjacent trough sections 13, 14 can occur with respect to each other; and since each trough section is connected to its actuating and supporting structure 12 at only one point, if one or more of the trough sections 13, 14 is caused to expand or contract, as by being subjected to excessively high or low temperatures, such variation in length of each trough section will have no tendency to buckle the conveyer trough 11 or to have any effect whatsoever upon the relationship of any part of the trough to actuating mechanism 12. It has been found that when the conveyer trough was constructed in accordance with the showing in my said issued patent, i. e., wherein each run of the conveyer consists of a single relatively long element of trough supported at two or more points upon its actuating mechanism, the efficiency with which the conveyer would operate would be impaired to an excessive degree when material at relatively high temperature would come in contact with the conveyer trough, as will readily be understood from the following description of the construction and operation of the supporting and actuating mechanism 12.

Supporting brackets 22 are rigidly mounted at intervals along the supporting framework 21 of the conveyer substantially corresponding to the respective lengths of the trough sections 13, 14, etc. Each of these brackets 22 preferably comprises a pair of horizontally spaced and vertically extending flanges 23 adjacent the upper edges of which a transversely extending shaft 24 is mounted. The shaft 24 is retained in position by any suitable means, such as a collar 26 and cotter pin 27 upon each end of the shaft. The shaft 24 extends through the central supporting hub 28 (see Figure 3) of a bell crank structure 29; and whereas this bell crank could, with equal advantage, be of single construction, in the modi-

fication shown it is double, i. e., each of the upper and lower arms 31 and 32, respectively, consists of a pair of spaced parallel lever members, all of which, along with the central hub 28, are in the form of a single unitary structure, preferably a casting.

A shaft 36 extends between the two parallel levers which comprise the upper arm 31 of the bell crank, this shaft 36 being parallel to the supporting shaft 24 and similarly retained in position as by a washer 37 and cotter pin 38 on each end of the shaft 36. This shaft 36 also extends through the lower end of a bracket 39 which is rigidly secured to and extends downwards from a trough section, say the trough section 14, adjacent the inlet end 16 thereof. Whereas any suitable means for mounting the bracket 39 upon its trough section may be employed, that which has been chosen for illustration herein consists of an angle iron 41 welded or otherwise rigidly secured to each of the lateral side walls of the trough sections 14 in such position that the under faces of their outwardly extending flanges 42 lie in substantially planar alignment with the under surface of the trough section 14, with the result that a transversely extending plate 43 secured against the under surfaces of the two outwardly extending flanges 42 as by bolts 44, is disposed in supporting relationship against the under surface of the associated trough section 14.

Another transversely extending shaft 46, also parallel to the central shaft 24, extends between the two levers which comprise the downwardly extending arm 32 of the bell crank 29, this shaft 46 also being retained in operative position as by a collar 47 and a cotter pin 48 on each end of the shaft 46. This shaft 46 serves as the means for connecting the downwardly extending arm 32 to an actuator bar 49, and the lower arms 32 of all the bell cranks 29 associated with a single run of conveyer trough are connected to the actuator bar 49 in such position thereon that they are disposed in parallel relationship with each other. When a run of conveyer composed of one piece and of such length as to require connection to more than one supporting and actuating mechanism was employed, owing to the fact that the upper arms 31 of all of the associated bell cranks 29 were connected to that run, binding of the moving parts of the structure would occur, and in some instances even actual buckling of the conveyer trough, when the trough was subjected to temperatures sufficiently high to cause an appreciable longitudinal expansion thereof. However, by constructing the trough of a plurality of separate and relatively slideable trough sections and connecting each trough section to but a single supporting and actuating mechanism in accordance with the principles of the present invention, I have provided means for compensating for any degree of expansion or contraction without any interference whatsoever with operating efficiency, inasmuch as each section of trough is free to move in telescopic relation with the section adjacent thereto.

It is optional whether the actuator bar 49 be of one piece throughout its entire length or be composed of a plurality of sections, each section being long enough to interconnect the shaft 46 of two adjacent actuating mechanisms 12. It is in this latter form that the actuator bar 49 has been illustrated. As clearly shown in Figure 3, one section 51 of the actuator bar 49 comprises two spaced parallel links 52 and 53, respectively,

through the ends of which the lowermost shaft 46 of two adjacent supporting and actuating mechanisms 12 extend, whereas the next adjacent section 54 of the actuator bar 49 consists of a single link 55, the ends of which are also carried by the transversely extending lower shaft 46 of two adjacent actuating mechanisms 12 and between the ends of the links of the next adjacent sections.

In order to impart oscillatory rotary motion to all of the bell cranks 29 simultaneously, means are provided for the longitudinal reciprocation of the actuator bar 49. One end of the actuator bar 49 is connected as by a wrist pin 56 with a connecting rod 57 at the outer end of which an eccentric strap 58 is secured. This eccentric strap 58 encircles an eccentric disc 59 which is carried by a shaft 61 journalled in bearings 62 upon a suitable supporting framework or platform 63. The shaft 61 also is provided with a driven pulley 64 connected as by V-belts 66 with the driving pulley 67 of a motor 68. Consequently, the rotary motion which is imparted to the eccentric disc 59 as the result of energization of the motor 68 causes the actuator bar 49 to reciprocate longitudinally, thereby imparting oscillatory rotary movement simultaneously to all of the bell cranks 29 with which that actuator bar is associated. Since the angularity between the upper and lower arms 31 and 32, respectively, of each bell crank is approximately midway between that of a right angle and a straight angle, this oscillatory movement of all of the bell cranks 29 supporting a single run of troughs 11 imparts an oscillatory, arcuate movement to the entire length of that run, developing the tossing action which, as explained in detail in my aforesaid Patent No. 2,123,189, causes material within the trough 11 to advance therealong in a succession of regularly repeated, step-by-step movements in spite of the fact that the conveyer 11 is either horizontal or even actually sloping upwards as much as 15° in the direction in which the material moves.

As hereinabove described, the bell crank of each of the supporting and actuating mechanisms is of integral construction instead of consisting of an upper arm keyed or otherwise releasably connected to a transverse shaft to which is also keyed the lower arm or lever which is connected to the actuator bar. Actual practice has proven that in the non-integral construction shown in my said prior patent wherein the upper and lower arms are connected to a transverse shaft by a key or the like, not only is a disproportionate amount of expense encountered in its manufacture, but its durability and dependability are impaired because of the fact that the continuously repeated and oppositely occurring stresses resulting from the reciprocatory movement of the actuator bar almost inevitably causes the keys to work loose. Moreover, it has been found that the reversal of torque imposed upon the transverse shaft which carries the angularly extending levers of the structure disclosed in my said prior patent will, if continued for a long period, set up crystallization in that shaft, causing its failure.

It was for the purpose of obviating these limitations of my prior mechanism that the integral structure of the bell crank mechanism 29 herein disclosed was developed. Actual practice has proven the improved structure of the present invention to be superior inasmuch as it transmits the energy from the actuator bar 49 directly to the bracket 39 of the trough in a straight, pivoted lever action and without having to translate the

energy to torque and without the necessity of having to use any keyed mechanism which is so apt to be short lived and, which, therefore, is relatively undependable.

Figures 6 and 7 show a modified form of my invention wherein two independent troughs 76 and 77 are both supported and actuated by a single series of supporting mechanisms 78 and a single actuator bar 79. As in the previously described modification, the troughs 76, 77, instead of being of one relatively long, unitary trough element, are composed of a plurality of trough sections 81, 82, etc., these sections being arranged in the same manner, as in the previously described modification of the present invention, i. e., with the delivery or outlet end of each section 81 nested within and supported by the inlet end of the next successive section in the direction in which material is carried by that conveyer. The bell crank structure 86 of each supporting and actuating mechanism 78, instead of consisting of but a single upper arm, is provided with a pair of upper arms 87 and 88 which are disposed at substantially 90° with respect to each other and at substantially 135° with respect to the lower arm 89, and upon opposite sides of the longitudinal axis thereof. The lower trough 76 is connected to one of the upper arms, say the arm 87 of the bell crank 86. Hence, when the actuator bar 79 moves to the right, as viewed upon Figure 6, the conveyor trough 76 is carried upward and to the left in arcuate motion, developing the tossing action which causes the material carried thereby to move along the conveyer to the left, as viewed in that figure. As this is occurring the other conveyor trough 77 which is connected as by an elongated bracket structure 91 to the other upper arm 88 of the bell crank 86, is moving in an arcuate path downwards and to the left, as viewed upon Figure 6. However, when the actuator bar 79 moves in the opposite direction, i. e., to the left, the conveyer 77 will be carried upward and to the right, developing the tossing action upon the material carried thereby which causes the material to advance to the right along the conveyer 77. Thus it may be seen that a single series of bell cranks 86 and a single actuator bar 79 can serve to operate two separate conveyers 76, 77 in such a manner as to cause material to flow in opposite directions thereupon.

Figures 8 and 9 illustrate a still further modified form of my improved conveyer mechanism wherein two conveyers extending angularly with respect to each other (or two angularly disposed runs of a single conveyer) are actuated by a single source of power, the actuator bar for the two conveyers (or for the two runs of the same conveyer, as the case might be) being so interconnected that the motion of the actuator bar proximal to the source of energy is transmitted simultaneously and coextensively to the other actuator bar.

In the modification illustrated in Figures 8 and 9, the discharge end 101 of one run 102 of a conveyer trough 103 inclines upwards slightly so that it terminates above the trough 104 of another conveyer (or of another run 106 of the same conveyer 102), the trough 104 extending angularly with respect to the trough 103, thus making it possible to carry material in two different directions. The series of supporting and actuating mechanisms 107 for the run 102 of trough 103 are carried by a suitable supporting structure 108 parallel to and below the trough 103; and the actuator bar 109 for the run 102 is disposed just

above the supporting structure 108, as in the first described modification. Similarly, the supporting structure 111 for the trough 104 of the run 106 is disposed below and parallel to that trough 106, but extends angularly from the end of the supporting structure 108. In a similar manner, the actuator bar 112 for the trough 106 is disposed above and parallel to the supporting structure 111 and, therefore, extends in an angular direction with respect to that of the actuator bar 109. Means are provided for so interconnecting the actuator bars 109 and 112 that they reciprocate simultaneously and coextensively. For this purpose a bracket 116 is provided upon the supporting structure 108 adjacent the end of the actuator bar 109, this bracket 116 carrying a pulley 117 which is revoluble upon a shaft 118 supported in the bracket 116. Rigid with the pulley 118 and extending downwards therefrom in parallelism with all of the lower arms 119 of the several supporting and actuating mechanisms 107 associated with the bar 109, is a lever 121, the lower end of this lever 121 being connected as by a suitable pin or shaft 122 to the actuator bar 109. Moreover, the length of the lever 121 coincides with that of each of the lower arms 119, with the result that as the bar 109 reciprocates, the same type and extent of rotary motion is imparted to the pulley 117 as that which is imparted to the several bell cranks of the actuating and supporting mechanisms 107.

Another bracket 126 rigid with the supporting structure 111 carries a transverse shaft 127 upon which a pulley 128 is revoluble; and a lever 129 rigid with and extending downwards from the pulley 128 is connected as by a pin or shaft 131 with the actuator bar 112. The bracket 126 also carries a vertical shaft (not shown) upon which two idler pulleys 136 and 137 are revoluble, the parts being so proportioned and arranged that the working faces of the idler pulleys 136 and 137 are in alignment with the upper and lower working faces, respectively, of both the driving pulley 117 and the driven pulley 128.

A cable 141 which in effect is an endless cable inasmuch as its ends are joined by a suitable tensioning device 142, extends around both the driving pulley and the driven pulley 128 and also around the idler pulleys 136 and 137, with the result that as reciprocatory rotary movement is imparted to the driving pulley 117 by the reciprocatory movement of the actuator bar 109, the driven pulley 128 is simultaneously reciprocated in rotary movement; and since both pulleys 117 and 128 are of the same effective diameter, the motion of these two pulleys will be coextensive. Therefore, even though the troughs 103 and 104 extend in angular directions with respect to each other, they will both be oscillated simultaneously and coextensively by a single source of power.

I claim:

1. In conveyer apparatus, a trough comprising a plurality of trough sections arranged in overlapping relation, and oscillating means supporting the inlet end of each of said sections, the outlet end of each of said sections being supported by the inlet end of the next successive section in the direction of movement of material carried by said section whereby the outlet end of each of said sections is caused to partake of the vertical movement of the inlet end upon which it is supported.

2. In conveyer apparatus, a trough comprising a plurality of trough sections arranged in overlapping relation, and oscillating means support-

ing the inlet end of each of said sections, the outlet end of each of said sections being slidably supported by the inlet end of the next successive section in the direction of movement of material carried by said section whereby the outlet end of each of said sections is caused to partake of the vertical movement of the inlet end upon which it is supported.

3. In conveyer apparatus, a trough comprising a plurality of trough sections arranged in overlapping relation, and oscillating means supporting the inlet end of each of said sections, the outlet end of each of said sections being supported upon and slidably axially with respect to the inlet end of the next successive section in the direction of movement of material carried by said conveyer whereby the outlet end of each of said sections is caused to partake of the vertical movement of the inlet end upon which it is supported.

4. In conveyer apparatus, a trough comprising a plurality of trough sections arranged in overlapping freely slidable relation with the outlet end of each section overlying and resting upon the inlet end of the next successive section in the direction of movement of material carried by said conveyer, and oscillating means for supporting the inlet end of each of said sections comprising a stationary bracket below said section, a bell crank comprising a pair of integrally joined arms

extending angularly with respect to each other and pivotally mounted on said bracket for movement about a horizontal axis adjacent the intersection of said arms, means pivotally connecting the upper end of said bell crank to the inlet end of the associated trough section, an actuator bar pivotally connected to the lower ends of all of said bell cranks, and means for reciprocating said actuator bar.

5. In conveyer apparatus, a trough comprising a plurality of trough sections arranged in overlapping freely slidable relation with the outlet end of each section overlying and resting upon the inlet end of the next successive section in the direction of movement of material carried by said conveyer, and oscillating means for supporting the inlet end of each of said sections comprising a stationary bracket below said section, a horizontally extending rockshaft carried by

6. In conveyer apparatus, a trough comprising a plurality of trough sections arranged in overlapping freely slidable relation with the outlet end of each section overlying and resting upon the inlet end of the next successive section in the direction of movement of material carried by said conveyer, and oscillating means for supporting the inlet end of each of said sections comprising a stationary bracket below said section, a bracket rigid with the associated trough section and extending downwards therefrom, a bell crank comprising a pair of integrally joined arms extending angularly with respect to each other, means pivotally connecting the upper end of said bell crank to said bracket, means supporting said bell crank for movement about a horizontal axis extending transversally through said

7. In conveyer apparatus, a trough comprising a plurality of trough sections arranged in overlapping freely slidable relation with the outlet end of each section overlying and resting upon the inlet end of the next successive section in the direction of movement of material carried by said conveyer, and oscillating means for supporting the inlet end of each of said sections comprising a stationary bracket below said section, a bracket rigid with the associated trough section and extending downwards therefrom, a bell crank comprising a pair of integrally joined arms extending angularly with respect to each other, means pivotally connecting the upper end of said bell crank to said bracket, means supporting said bell crank for movement about a horizontal axis extending transversally through said

8. In conveyer apparatus, a trough comprising a plurality of trough sections arranged in overlapping freely slidable relation with the outlet end of each section overlying and resting upon the inlet end of the next successive section in the direction of movement of material carried by said conveyer, and oscillating means for supporting the inlet end of each of said sections comprising a stationary bracket below said section, a bracket rigid with the associated trough section and extending downwards therefrom, a bell crank comprising a pair of integrally joined arms extending angularly with respect to each other, means pivotally connecting the upper end of said bell crank to said bracket, means supporting said bell crank for movement about a horizontal axis extending transversally through said

9. In conveyer apparatus, a trough comprising a plurality of trough sections arranged in overlapping freely slidable relation with the outlet end of each section overlying and resting upon the inlet end of the next successive section in the direction of movement of material carried by said conveyer, and oscillating means for supporting the inlet end of each of said sections comprising a stationary bracket below said section, a bracket rigid with the associated trough section and extending downwards therefrom, a bell crank comprising a pair of integrally joined arms extending angularly with respect to each other, means pivotally connecting the upper end of said bell crank to said bracket, means supporting said bell crank for movement about a horizontal axis extending transversally through said

10. In conveyer apparatus, a trough comprising a plurality of trough sections arranged in overlapping freely slidable relation with the outlet end of each section overlying and resting upon the inlet end of the next successive section in the direction of movement of material carried by said conveyer, and oscillating means for supporting the inlet end of each of said sections comprising a stationary bracket below said section, a bracket rigid with the associated trough section and extending downwards therefrom, a bell crank comprising a pair of integrally joined arms extending angularly with respect to each other, means pivotally connecting the upper end of said bell crank to said bracket, means supporting said bell crank for movement about a horizontal axis extending transversally through said

bell crank adjacent the intersection of said arms, an actuator bar pivotally connected to the lower ends of all of said bell cranks, and means for reciprocating said actuator bar.

7. In conveyer apparatus, a pair of troughs arranged in spaced parallel relation and means for supporting said troughs and imparting oscillatory movement thereto comprising a plurality of bell cranks, each comprising a pair of integrally joined arms extending upwards angularly with respect to each other, and a lower arm integral with said upwardly extending arms and extending downwards from the intersection thereof, means pivotally connecting one of said upwardly extending arms of each of said bell cranks to one of said conveyers, means pivotally connecting the other of said upwardly extending arms of each of said bell cranks to the other of said conveyers, means supporting each of said bell cranks for movement about a horizontal axis extending transversally of said bell crank adjacent the intersection of said arms thereof, an actuator bar pivotally connected to the lower ends of all of said bell cranks, and means for reciprocating said actuator bar.

8. In conveyer apparatus, a pair of troughs arranged in spaced parallel relation, each of said troughs comprising a plurality of trough sections arranged in overlapping relation with the outlet end of each of said sections overlying the inlet end of the next successive section in the direction of movement of material carried by that trough, and means for supporting said troughs and imparting oscillatory movement thereto comprising a plurality of bell cranks, each comprising a pair of integrally joined arms extending upwards angularly with respect to each other, and a lower

arm integral with said upwardly extending arms and extending downwards from the intersection thereof, means pivotally connecting one of said upwardly extending arms of each of said bell cranks to one of said conveyers, means pivotally connecting the other of said upwardly extending arms of each of said bell cranks to the other of said conveyers, means supporting each of said bell cranks for movement about a horizontal axis extending transversally of said bell crank adjacent the intersection of said arms thereof, an actuator bar pivotally connected to the lower ends of all of said bell cranks, and means for reciprocating said actuator bar.
